UNITED STATES PATENT OFFICE.

ALPHEUS WOODS MONTGOMERY, OF NEW YORK, N. Y.

PROCESS OF MANUFACTURING TARRED ROPES AND YARNS.

SPECIFICATION forming part of Letters Patent No. 312,286, dated February 17, 1885.

Application filed November 2, 1883. (No specimens.)

To all whom it may concern:

Be it known that I, ALPHEUS W. MONTGOMERY, a citizen of the United States, residing in the city, county, and State of New York, 5 have invented certain new and useful Improvements in the Process of Manufacturing Tarred Ropes and Yarns; and I do hereby declare that the following is a full, clear, and exact description of the invention, which will enable others skilled in the art to which it appertains to make and use the same.

Yarns and ropes are tarred because the preservative qualities of the tar render them impervious to moisture and dampness and prevent decay.

The practice of my invention hereinafter described causes the tar to permeate and protect more perfectly the structure and fibers of the rope, while the rope itself, when coated with tar by said process, is far more pliable in all temperatures than that manufactured by the methods at present employed.

I have discovered that the chief difficulties in the way of producing a more perfect product under the processes of tarring ropes now in use arise from the fact that the fibers of the yarns or ropes to be treated contain a certain amount of natural and artificial moisture, which prevents the tar entering and thoroughly permeating all the fibers, interstices, and cells of the material; also, that said fibers and cells, when brought in contact with the tar, are in a contracted and inefficient condition, and tend to stiffen and congeal the melted tar; and, 35 also, that the most valuable constituents of the tar for protecting the fiber of rope or yarns and keeping them pliable, being very volatile, are to a large extent vaporized and lost by heating the tar bath to the temperature necessary to obtain and maintain a proper degree of fluidity under ordinary conditions.

The hemp used in the manufacture of yarns and ropes as it is usually received in bales by rope-makers contains a certain amount of natural moisture. It is also usual in the process of manufacture to moisten or dampen the hemp before it goes to the spindles, for the purpose of preventing waste and insuring easy working. The consequence of this natural and artificial moisture in the fiber is that when the tar is applied it does not thoroughly permeate and saturate the fibers, which are therefore more

liable to decay than they would be if thoroughly saturated.

The process of tarring yarns and ropes heretofore commonly in use has been to pass them, while in a state containing more or less natural and artificial moisture, as above described, and while at normal temperature, through a tar bath made by placing the tar in a tank or other receptacle of a convenient size and shape, and heating it, by means of steam-coils or other applications of heat, to a temperature of, say, 200° Fahrenheit and upward, the precise degree of heat employed depending somewhat upon the condition and temperature of the surrounding atmosphere. Through this bath the yarns or ropes are passed by any convenient mechanism.

In this process there are the following defects: First, the presence of moisture in the fiber prevents the due absorption of the tar into its structure and fiber; second, the rope being at normal temperature when it enters the bath tends to congeal the tar which comes in actual contact therewith and makes it incapable of entering into the smaller interstices of the material; third, heating the bath to the temperature above described causes the more volatile portions of the tar, and such as more readily permeate the fiber and are most valuable in preserving it, to evaporate and escape. Ropes made from yarns tarred in such a manner lose their pliability to a great extent, and in cold weather particularly the tar in the ropes becomes hard and rubs and wears the fiber.

In the process which I have invented and for which I claim a patent I have avoided these defects in the following manner: I thoroughly heat and dry the ropes or yarns before they are treated with tar, and while they are in this heated condition I pass them through the tar bath, for the purposes described.

By thoroughly heating and drying the yarns or ropes before they are immersed in the tar I expel therefrom all moisture and dampness, and expand and distend the cells, whereby their receptivity and capacity for absorbing the tar are greatly increased, and by passing the ropes and yarns through the tar bath while they are in this heated condition I am able to keep the tar in the bath at a lower temperature than is possible under the processes heretofore employed, whereby evaporation and waste of the

most valuable constituents of the tar are avoided, and consequently the quality of the product greatly improved. It will be observed that, to whatever temperature the tar bath 5 may be raised, the heated rope will absorb more tar than it would if introduced at normal temperature, because the fibers are expanded, and because the heated rope does not chill the tar coming in actual contact therewith, but even renders the same more fluid.

Experience has demonstrated that tar only raised to a temperature sufficient to prevent stringiness will not be sufficiently limpid to enter into the pores of and thoroughly saturate the rope, unless the rope itself be raised to a high temperature, in which case the heat of the rope has the effect of rendering limpid the particles of tar in actual contact therewith, which do not, under these conditions, lose by 15 evaporation their more volatile portions, being confined within the inclosing mass of cooler tar. In this case the rope itself is used as a means of raising the temperature of the tar with which it is saturated to the necessary 20 point, and introducing and applying the heat in this manner is an important feature of my invention. In other words, the tar is only partially heated by the application of heat to the bath as a whole, it being subsequently raised 25 to the temperature necessary in rope-treating by the heat introduced with the rope itself, whereby, as herein described, improved results are effected.

In the case of yarns, the method I employ 30 and which I prefer is to pass them, just before immersion in the tar bath, over heated cylinders. In the case of ropes, a longer exposure to the action of heat may be necessary, according to the size of the rope, and this may be 35 accomplished by placing the coil of a rope in a hot oven, or by any other means by which it may be thoroughly dried and heated to the proper 40

temperature immediately previous to being passed through the tar bath.

The yarns or ropes, before being passed 45 through the tar bath, should be heated to as high a degree of temperature as is possible without injuring the fiber.

In concluding this specification I desire to 50 remark that instead of passing the dried rope or yarn through the tar bath while in a heated state I may allow the rope to cool before it is introduced therein, and still produce a product far superior to those manufactured by the ordinary processes at present employed. 55

I am aware that papers and felts have been heated preliminarily to coating the surfaces thereof with wax, paraffine, varnish, and other waterproofing material, for the purpose of making them absorb the same more readily; 60 but that is not the point of my invention, the object of which is to improve the rope by causing it to absorb the more volatile elements of the tar without heating the tar bath itself high enough to drive off the elements with 65 which I desire to impregnate the rope, as stated in the following claim.

What I claim as my invention, and desire to 70 secure by Letters Patent, is—

The process herein described of treating 75 rope with tar to cause it to absorb the more volatile portions thereof, which process consists of heating the tar to a temperature just high enough to render it fluid, but not high enough to expel its lighter oils, and of then introducing into the tar bath rope raised to a temperature higher than that of the tar, to produce a tarred rope which is limber and pliable at all temperatures, substantially as described.

ALPHEUS WOODS MONTGOMERY.
